(57) **CLAIM**

The ornamental design for a vehicle wheel rim, as shown and described.

DESCRIPTION

1. Vehicle wheel rim

1.1: is a perspective view of a vehicle wheel rim embodying my new design;

1.2: is a front elevation view thereof;

1.3: is a right side elevation view thereof;

1.4: is a left side elevation view thereof;

1.5: is a top plan view thereof;

1.6: is a bottom plan view thereof; and

1.7: is an enlarged and partial front elevation thereof.

The broken lines in the reproductions illustrate portions of the vehicle wheel rim that form no part of the claimed design.
